WILLIAM P. REILLY

BY
Richard Cook
ATTORNEY

UNITED STATES PATENT OFFICE.

WILLIAM P. REILLY, OF TACOMA, WASHINGTON.

TRAIN-PIPE CONSTRUCTION.

Application filed October 9, 1923. Serial No. 667,484.

To all whom it may concern:

Be it known that I, WILLIAM P. REILLY, a citizen of the United States, and a resident of Tacoma, Pierce County, Washington, 5 ton, have invented certain new and useful Improvements in Train-Pipe Constructions, of which the following is a specification.

This invention relates to improvements in train pipe construction, more particularly 10 to the embodiment of the signal and brake air lines on a train in a single pipe where previously two have been used.

The object of the invention resides in the provision of a longitudinally divided train pipe through which the signal and brake air may flow, together with similarly divided connections between cars and connecting valves each with a single rotary plug valve for controlling both the brake and 20 signal air.

Other objects of the invention reside in the details of construction and combination of parts as described in the following specification and as set forth in the claim terminating the same.

In accomplishing these and other objects of the invention, I have provided the improved details of construction, the preferred forms of which are illustrated in the 30 accompanying drawings, wherein—

Figure 1 illustrates a part of a train pipe line embodied by the present invention, some of the parts being in section for better illustration.

Figure 2 is a sectional view, illustrating the construction of one of the connecting valves used in the system.

Referring more in detail to the drawings— 40 1 and 2, respectively, designate pipes that lead from a signal line mechanism and the brake control operating valve, neither of which are herein illustrated, but which would be of the type usually used in air brake systems of railway trains. These pipes connect with one end of a train pipe 3 with which connection may be made as by means of the branch pipe 4 with the brake cylinder, not shown, wherein there is a piston operated by air pressure to actuate 45 the wheel braking mechanism. The pipe 3 is longitudinally divided by a partition plate 5 thereby providing separate air passages 6 and 7, with which, at one end of the line,

the pipes 1 and 2, respectively, communicate.

8 designates what may be a flexible coupling pipe for use between the cars of a train for connecting the pipes 3 with which each car would be equipped. Superimposed between the pipes 3 and 8 is a connecting 55 valve 9, the channel of which is divided by longitudinally extending partition 10 forming two separate channels that connect the channels of the pipes 3 and 8. This valve has a single plug 11 with a divided port for controlling both valve passages, and the plug is rotatable by means of a handle 12 to control the passage of air through the train and signal lines.

To each train pipe there is also connected a branch 15 that provides connection between air channels 6 and a signalling device, not shown. The method of using these devices and the brake control mechanism is well known and will not be described farther.

Assuming that the cars of a train are so equipped and that the train lines between cars are connected by the flexible couplings, it is apparent that a single pipe is employed where previously two have been required. It is also apparent that a single valve and connecting hose are used where previously there were two. By using the 70 construction, above described, the cost of equipment is greatly reduced, and a more 75 easy connecting system is provided.

Having thus described my invention, what I claim as new therein and desire to 80 secure by Letters Patent, is:

In a train control and signal system, the combination with signal and brake control air lines of a train line pipe divided longitudinally to form separate passages having 85 connection respectively with said signal and brake control air lines, a flexible similarly divided tube for joining the train line pipes of adjacent cars in a train and a valve housing connecting the train line pipe and connecting pipe and having a single plug valve operable to control the flow through 90 both of said passages.

Signed at Tacoma, Pierce County, Washington, this 28th day of September 1923.

WILLIAM P. REILLY.
